[57] CLAIM

A new and ornamental design for a combined shovel and lift attachment, as shown and described.

DESCRIPTION

FIG. 1 is a perspective view of the combined shovel and lift attachment of the first embodiment of my new design;

FIG. 2 is a side elevational view of the right side of FIG. 1, the left side being a mirror image thereof;

FIG. 3 is a top plan view of FIG. 1;

FIG. 4 is a bottom plan view of FIG. 1;

FIG. 5 is a front elevational view of FIG. 1;

FIG. 6 is a rear elevational view of FIG. 1;

FIG. 7 is a perspective view from the handle end of the combined shovel and lift attachment of FIG. 1;

FIG. 8 is a front perspective view of the combined shovel and lift attachment of the second modification of my new design;

FIG. 9 is a side elevational view of the right side of FIG. 8, the left side being a mirror image thereof;

FIG. 10 is a top plan view of FIG. 8;

FIG. 11 is a front elevational view of FIG. 8;

FIG. 12 is a bottom plan view of FIG. 8;

FIG. 13 is a rear elevational view of FIG. 8;

FIG. 14 is a perspective view of the combined shovel and lift attachment of the third modification of my new design;

FIG. 15 is a side elevational view of FIG. 14, the left side being a mirror image thereof;

FIG. 16 is a top plan view of FIG. 14;

FIG. 17 is a front elevational view of FIG. 14;

FIG. 18 is a bottom plan view of FIG. 14; and

FIG. 19 is a rear elevational view of FIG. 14.
